US0D1053326S

(12) **United States Design Patent** (10) **Patent No.:** **US D1,053,326 S**
(45) **Date of Patent:** **** Dec. 3, 2024**

(54) **AIR CONDITIONING HOUSING**

(71) Applicant: **Dometic Sweden AB**, Solna (SE)

AU 2004202967 3/2011
AU 2007200788 9/2011

(72) Inventors: **Rickard Hederstierna**, Hägersten (SE);
Samuele Meda, Chichester (GB)

(Continued)

(73) Assignee: **Dometic Sweden AB**, Solna (SE)

(**) Term: **15 Years**

(21) Appl. No.: **29/915,796**

(22) Filed: **Nov. 3, 2023**

(57) **CLAIM**

The ornamental design of an air conditioning housing as shown and described.

DESCRIPTION

FIG. 1 is a first perspective view of a design of an air conditioning housing;

FIG. 2 is a second perspective view of the air conditioning housing of FIG. 1;

FIG. 3 is a first side view of the air conditioning housing of FIG. 1;

FIG. 4 is a second side view of the air conditioning housing of FIG. 1;

FIG. 5 is a front view of the air conditioning housing of FIG. 1;

FIG. 6 is a rear view of the air conditioning housing of FIG. 1; and,

FIG. 7 is a top view of the air conditioning housing of FIG. 1.

The broken lines and the areas within them depict portions of the air conditioning housing that form no part of the claimed design.

1 Claim, 7 Drawing Sheets
